COLLAR PROTECTOR FOR SOFT SHIRTS

James W. Steele, North Kansas City, Mo.

Application August 23, 1948, Serial No. 45,765

1 Claim. (Cl. 223—83)

1

The present invention relates to means or devices used for protecting the collar portions of shirts, with particular reference to the collars of soft shirts, or what are known as sport shirts, which are ordinarily finished in a relatively limp condition.

A primary purpose of the present invention is to devise a practical and very simple device which will afford the desired protecting means for the collars of this type of shirt, with a view to supporting or bracing it against undue crushing, and also be so designed and constructed as to retain its position within the collar and not readily fall out of the finished shirt when the same is handled in the usual manner.

It is also sought to provide an efficient form of device that may be readily constructed from ordinary cardboard material in an economical manner and with practically no waste in said material.

With these general objects in view, as well as various minor objects as will appear in the course of the detail specification, the invention will now be described by reference to the accompanying drawing illustrating a preferred form of the construction, after which those features and combinations deemed to be novel and patentable will be particularly set forth and claimed.

In the drawing—

Figure 1 shows a front perspective view of the collar portion of a soft or "sport" type of shirt, with my new and improved supporting device inserted therein, in collar supporting and protecting position;

Figure 2 is an enlarged perspective view of the supporting or protecting device removed from the shirt collar;

Figure 3 is a plan view of the device as die-cut from a sheet of cardboard material; and

Figure 4 is a detail sectional view, representing a section taken on the line 4—4 of Figure 1, but on an enlarged scale.

With reference to the general type or class of collar supports in common use, which are adapted as a protective support for collars that are starched or sized in the finishing operation, these supporting devices comprise a band or supporting strip which is inserted between the folds of the collar, and the device is adapted to be retained in this position, so long as the support is in use. With sport shirts and the like, which are made of soft material which will not permit starching or sizing, so that the collars are left in a limp or flimsy condition even in the finished state, a somewhat different type of supporting

2

device is desirable, which will not only facilitate its application into supporting position but also provide the required stiffness or rigidity of the supporting function for protecting the collar from becoming mussed and disarranged in handling or packaging, as well as preserving the garment in its neatly finished condition up to the time of use.

For providing an effective device for this purpose I make use of a construction illustrated in the accompanying drawing, which is die-cut from suitable cardboard material to provide a pair of oblong bands of approximately equal length, and comprising a collar neckfold engaging band 6 (which may be termed the front band portion of the device), and also an inner or bracing band or strip 8 (which I may term the rear band portion of the device) having the same general curvature as illustrated in Figure 3 and connected with the band 6 along a hinge or fold line designated generally by the reference numeral 10. As shown, the two bands 6 and 8 are of approximately the same width as well as length, and the connection between the bands is made along a weakened fold line which may be produced by means of a series of perforations or slits 12 extending from points adjacent the ends of the bands to points short of the mid-point of said fold line 10; this leaves positive or unbroken connecting portions, not only between said slits or perforations 12 but also at the ends of said fold line as indicated at 10', as well as along the somewhat extended midportion 10" of said fold line—or between the inner ends of said series of slits or perforations 12—as illustrated in Figures 2 and 3.

The purpose of this folding band structure is to provide a bracing or supporting means of an inverted-V type within the collar opening—the base of the support being the back portion of the shirt or package containing the same, and the nature of the construction being such that the rear band 8 can not be folded into actual engagement with the front band 6, so that it is at all times obliged to assume a spaced supporting or bracing position, in rearwardly inclined relation to said front band 6. This feature is of particular importance with relation to the middle portion of the device where the aforesaid unbroken portion 10' of the hinge or fold line extends for some distance and is thus adapted to provide an approximately straight and relative rigid hinge or fold line opposite the front ends of the collar portions 20 of the shirt 21, where the

maximum protecting or bracing action is most needed for resisting any crushing action at the critical point where this protection is most essential.

Referring to the contour of the longitudinal edges of the bands 6 and 8, it may be explained that these are not of strictly circular design but are of such curvature that on folding of said bands along the fold line 10 the outer longitudinal edges of the bands will maintain a substantial continuous supporting engagement throughout their length with the horizontal inner face of the back portion of the shirt—as represented in Figure 4, while said fold line 10 conforms approximately to the upper fold line of the collar 21, as shown in Figures 1 and 4.

Referring also to the middle connecting portion 10' between the bands 6 and 8, this also has the effect of helping to distribute the bending effect at the middle portions of the bands, so as to prevent the bending of the same at merely one central point when the bands are being inserted into operative or supporting position within the collar, as above explained.

The middle portion of the front band 6 is illustrated as provided with a hinged wing tab device 15 of somewhat elongated or oblong design which may be conveniently die-cut from the said midportion of the band 6, to form end wing portions 17 of any appropriate or desired contour. As shown, this wing tab device is left connected with the band 6 by means of a small tablike element 18 having a short unbroken connecting line 18' adjacent to and directly below the midportion 10' of the main fold line 10. Thus, the tab device 15 may be swung outwardly and upwardly with reference to said connecting hinge line 18' to facilitate the insertion of the main band portions 6 and 8 within the collar opening, and thereafter swung back to insert the inner portions 17 of the tab beneath the upper front corners of the collar. In this position the tab member provides not only an efficient retaining means for holding the support in place at the front of the collar but further acts as a bracing means for reinforcing the supporting action of the device at the front meeting ends of the collar, as illustrated in Figures 1 and 4.

A very practical and efficient device is thus provided for carrying out the desired objects of my invention, as a means for providing adequate protection as regards the collar portions of soft shirts, such as "sport" shirts and the like. The device is readily inserted in the manner above indicated, into supporting position within the collar opening, as illustrated in Figure 1, in which position the ends of the device extend into engagement with the opposite ends of the relatively straight rear portion of the collar; and as the construction of the bands 6 and 8 as illustrated and described is of such a character (as above explained) that when the lower supporting edges of both bands are engaged with the back portion 22 of the shirt, said bands can not be crowded any closer together, it is therefore evident that the folding of said bands is limited to the inverted V-shaped relation—as represented in the cross-sectional view shown in Figure 4 of the drawing. In this position the device obviously provides a rigid or noncollapsible supporting structure which will resist any ordinary downward pressure that might otherwise produce a crushing action or effect on the collar; and moreover, the ends of the rear band 8 being engaged in abutting relation to the opposite ends of the

relatively straight rear portion of the collar 21, the support is thereby retained against any tendency to move out of its supporting and bracing position. Preferably, also, the ends of said rear band portion 8 are cut on a bias to provide rearwardly inclined end edges for still more effectively resisting any such tendency of the support to become dislodged from the position illustrated in Figure 1 of the drawing. As a matter of fact any downward or forward pressure exerted against the rear ends of the support simply results in producing an upward or lifting action at the front portion of the support—opposite the meeting ends of the collar.

The provision of the wing tab device not only serves a supporting function, for reinforcing the front portion of the collar, but also a retaining function since its position between the folds of the collar effectively counteracts any tendency of the support to move upwardly out of its operative or supporting position.

In this connection it is also pointed out that an important feature of the invention lies in the fact that the construction of the wing tab device leaves the lower front portion of the front band 6 intact, whereby said front band is made to serve as a continuous supporting and bracing means, in engagement with the front of the shirt all around the collar, in cooperation with the rear band 8 of the support.

Moreover, this feature of the invention serves a still further novel function, by virtue of the fact that the cutting out of the wing tab device from the front band 6 also leaves an inner edge (indicated at 6') adapted to serve and function as a shoulder for engagement with the interior front portion of the collar, thus reinforcing the retaining function of the wing tab device by counteracting any tendency of the support to move out of its operative or supporting position (see Figure 4).

While I have illustrated and described what I have found to represent a practical and efficient as well as what I now regard as the preferred form of construction for embodying my improved features of construction, it will of course be apparent that minor changes or modifications may readily be made within the scope of what I regard as my invention. For the provision of the inverted-V type of braced or reinforced supporting structure is not considered as strictly limited to the specific relative sizes or proportions shown, or to the means illustrated for constructing the hinge or fold line between the front and rear band sections; and moreover, the specific design and location, or mode of connection between the auxiliary wing tab device 15, may obviously be varied while at the same time preserving its functional characteristics as herein set forth. As a matter of fact the wing tab device 15 may be altogether omitted from the support so far as the primary features of my invention are concerned.

All such minor changes and modifications are, therefore, regarded as embraced within the scope of my invention, as defined by the appended claim.

Having thus described my invention, what I claim and desire to secure by Letters-Patent is:

A one-piece collar supporting and protecting device for finished and folded shirts, comprising a collar supporting band for engaging the inner neck-engaging face of the neck fold of the collar, and a bracing band substantially coextensive with

said supporting band and hingedly connected with the upper edge thereof along a longitudinal slightly curved fold line allowing only limited folding of the bands short of complete collapsing of the bracing band within said supporting band whereby said bracing band is maintained in rearwardly inclined relation to the supporting band when the device is in supporting position inside the shirt collar with the lower edges of both bands in supporting engagement with the inner face of the back portion of the shirt, and said supporting band being formed with a wing tab portion struck out from its front portion midway between the ends thereof and having the upper edge of said wing tab hingedly connected with 15 said supporting band adjacent to the upper margin thereof, whereby said wing tab may be in-

serted into retaining engagement between the upper front corners of the shirt collar.
